LARYNGECTOMIC SHIELD

Charles M. Taintor, Southport, Conn.

Application August 16, 1950, Serial No. 179,658

4 Claims. (Cl. 128—132)

1

This invention relates to a shield to be worn after a laryngectomy as a protective covering over the neck opening left for breathing purposes by this operation. The great convenience of my shield is that it maintains a free air passageway after prolonged use by the wearer.

Persons suffering from chronic laryngitis frequently undergo a laryngectomy in which the larynx or voice box situated at the top of the trachea is completely removed. In this operation, the normal passage from the nostrils to the windpipe is surgically sealed off and an open hole is left in the suprasternal notch. This hole connects with the windpipe and provides the air necessary for breathing.

Much difficulty is encountered by the laryngectomee in protecting his outer garments from the mucus which normally lubricates the larynx cords and is forcibly ejected from the open hole. I solve this difficulty by providing a protective covering of an absorption material consisting of gauze, cheesecloth or the like held by a rigid shield member in proximity to but not touching the neck opening. This shield is formed to comfortably fit the wearer and is quickly and easily positioned by a resilient tab with a slot which slips over the top shirt button or the like.

I have discovered that by holding the absorption material slightly removed from the neck opening my device can effectively function over a prolonged period of time because mucus is readily absorbed and the air passageway remains unobstructed. Otherwise there is a tendency for the absorption material to cling to the opening and thus allow mucus to accumulate in the trachea. This reduces the air supply below that required for normal activity by the laryngectomee.

Further advantages of this invention may readily be understood by reference to the accompanying drawing which shows an illustrative example of my specification.

Fig. 1 is a front view showing the shield in position over the neck opening; Fig. 2 is a vertical sectional view taken on the line 2—2 of Fig. 1; Fig. 3 is a front view of this invention; Fig. 4 is a vertical sectional view taken on line 4—4 of Fig. 3; Figs. 5 and 6 are horizontal sectional views taken on lines 5—5 and 6—6 respectively of Fig. 3 and show diminishing curvature of the shield.

Shield 10 consists of a solid piece of plastic in the general form of a scoop which gradually flattens so that edge 12 is only slightly curved. A multi-ply covering of sterile gauze 14 affixed by any suitable means to approximately three quarters of the inside surface of shield 10 provides the pad necessary for mucus absorption. Resilient tab 16 mounted on shield 10 has a slot 18 adapted to fit over the wearer's top shirt button and hold the shield in position over the neck opening.

2

Obviously a wide variety of structures may be used to hold the absorption material in proximity to but not touching the neck opening, but I find that the preferred structure shown is the most comfortable and efficient. To place the shield in position slot 18 is easily and conveniently slipped over the top shirt button. This holds the shield with the slightly curved edge 12 fitted comfortably against the base of the neck. At this end, corners of the shield are diagonally cut to avoid interference with normal neck movement. Side edges 20 follow the natural contour of the body and are held snugly against the chest by resilient tab 16 and the slight pressure exerted by the wearer's shirt and tie. In the preferred form of my invention, tab 16 consists of a narrow strip of resilient material. One end is secured to the shield's mid-section with the slotted end extending adjacent to the shield and over its central top portion. Thus, when slot 18 is fitted over a supporting button on the wearer's outer garment, the resilient tab member tends to assist in holding shield side edges 20 against the body.

Any suitable material may be used in forming the rigid shield but the important thing is that it be impervious to the mucus so that even if the absorption material becomes saturated, adequate protection of the wearer's outer garments is still provided. A sheet of plastic is light and excellently adapted for this purpose.

With the shield held as described, I find that a substantial portion of the air used for breathing enters under the curved open end portion of the shield and in passing over the wearer's body there is a tendency for this air to be heated and filtered. This is highly important to the laryngectomee, whose trachea becomes painfully inflamed by dust particles or air which is at a temperature below 50° F. In addition, the area between the shield and the body is sufficiently large so as not to increase admixture of exhaled carbon dioxide gas with inhaled atmospheric air over that normally experienced when the shield is not in use.

It will be understood that it is intended to cover all changes and modifications of the preferred embodiment of the invention herein chosen for the purpose of illustration which do not constitute departures from the spirit and scope of the invention.

50 What I claim is:

1. A shield with an absorption pad in the general form of a scoop which gradually flattens to form a substantially plane surface at one end portion, said shield adapted to be positioned on the wearer's body over the neck opening left by a laryngectomy with such end portion fitted against the neck and with its side edges fitted against the chest and means for holding the shield whereby the mucus forcibly ejected from said opening is collected.

2. A structure as specified in claim 1 in which the holding means consist of a tab having a slot in one end portion positioned to fit over a supporting button on the wearer's garment and hold the shield in position over said opening.

3. A structure as specified in claim 2 in which the tab consists of a narrow resilient strip of material with one end portion secured at the shield's mid-section, and with the slotted end extended to the central top portion of said shield in flexible relationship thereto whereby the tab when fitted over a supporting button on the wearer's garment assists in holding the shield side edges against the wearer's body.

4. A shield with an absorption pad adapted to fit over the neck opening left by a laryngectomy and to hold said pad in proximity to but not

touching the opening and said shield having a tab with a slot in one end portion positioned to fit over a supporting button on the wearer's garment whereby the mucus which is forcibly ejected from such an opening is collected.
